UNITED STATES PATENT OFFICE

HENRY L. KEHL, OF PITTSBURGH, PENNSYLVANIA, ASSIGNOR TO JONES & LAUGHLIN STEEL CORPORATION, OF PITTSBURGH, PENNSYLVANIA, A CORPORATION OF PENNSYLVANIA

TABLE FOR GRINDING APPARATUS

Application filed April 2, 1929. Serial No. 351,848.

This invention relates generally to tables for feeding bars to grinding apparatus and receiving the ground bars from the grinding apparatus. It relates more particularly to tables of the character above referred to in which the bars are fed to and delivered from the grinding apparatus automatically. The bars are given a rotating and forward movement before entering the grinding apparatus, and the speed of this movement is substantially equal to that imparted to the bars by the regulating wheels of the grinding apparatus.

In tables of the general types referred to and which have been used heretofore, rotation of the bars before entering the grinding apparatus has been imparted by hand. When the hand method is employed it is necessary to overcome the inertia of the bars in bringing them up to the proper grinding speed. While the bars are attaining the proper grinding speed the grinding apparatus acts unevenly on the bars resulting in flat spots and a reduced diameter of the bars adjacent their ends.

In devices heretofore in general use no means has been provided for maintaining the forward and rear ends of the bars in proper alignment with the grinding apparatus. If the ends of the bars are out of alignment, the bars strike the face of the grinding wheel at an angle and cause a reduction in the diameter of the bars. For example, a bar 20 feet long having its free end 1/32 of an inch out of line with the end of the bar in contact with the grinding apparatus reduces the diameter of the bar about 5/10000 of an inch at the edge of a grinding wheel having a 4 inch face.

In devices heretofore in use when it becomes necessary to operate upon bars of a different size, it has required a great deal of time to make the necessary adjustments of the guides and means for rotating the bars.

All of these disadvantages are overcome by my invention. In accordance with one form of the present invention, the bars are fed to the grinding apparatus by means of rotating conical discs contacting with the bottoms of the bars. All of the discs along the

tables are rotated from a common drive shaft which rotates the discs at the same speed. The center line of the discs are slightly out of alignment with the center line of the bars. This arrangement not only rotates the bars around their own axes but also imparts a longitudinal movement thereto. The speed of the rotating conical discs is such that the speed of the bars as they enter the grinding apparatus is substantially equal to that imparted by the regulating wheels of the grinding apparatus. In this manner the inertia of the bars is overcome before the bars enter the grinding apparatus. The whole length of the bar is therefore subjected to a uniform grinding action resulting in the bar having an even diameter throughout its length.

The forward and rear ends of the bars are maintained in alignment by providing the table with a torsion shaft having pinions mounted at its ends. The pinions run in racks provided on the supporting structure. The table is moved sidewise by means of its attachment to a part (not shown) of the grinding apparatus which is operated by hand. The provision of the pinions and racks insures proper alignment of the ends of the bars.

The necessary adjustments for operating upon different sized bars is accomplished by rotation of a hand wheel. The hand wheel is secured to a shaft extending the length of the table and has bevel pinions secured thereto which mesh with bevel pinions secured to an oppositely threaded screw. Rotation of the screw moves the guides in a horizontal direction. Movement of the guides in a horizontal direction automatically causes the conical discs which rotate the bars to be moved upwardly or downwardly so as always to maintain the center line of the bars in the proper grinding relationship.

In the accompanying drawings which illustrate the present preferred embodiment of my invention;

Figure 1 is a diagrammatic representation of the whole apparatus,

Figure 2 is a plan view of the feed table,

Figure 3 is an elevation of the feed table,

Figure 4 illustrates the adjusting mecha-

nism for operating upon different size bars,

Figure 5 is an end elevation of the feed table showing the rack and pinion for maintaining the ends of the bars in alignment,

5 Figure 6 is an end view of the adjusting mechanism shown in Figure 4.

Figures 7 and 8 are sections taken respectively on the lines VII—VII and VIII—VIII of Figure 4, and

10 Figure 9 is an end view of a guide for guiding the bars along the table.

Referring to Figure 1, there is shown a feed table 2 which delivers the bars A to a grinding apparatus 3. The ground bars are received from the grinding apparatus on a receiving table 4. The bars are delivered to the feed table 2 from a rack 5 by means of the arms 6 mounted on a shaft 7. After being ground and received upon the receiving table 4 the bars are transferred from the receiving table to a rack 8 by arms 9 mounted on a shaft 10.

The means for maintaining the ends of the bars in alignment is illustrated in Figures 2, 3 and 5. The table is mounted on wheels 12 running on guide tracks 13 secured to supports 14. One of the wheels 12 at each end of the table carries a torsion shaft 15 which extends the length of the table. Pinions 16 secured to each end of the torsion shaft mesh with racks 17 carried by the supports 14. The table is moved sideways by means of its attachment to a part of the grinding apparatus which is operated by hand. The provision of the pinions 16 and racks 17 insures that the ends of the bars will be maintained in alignment.

The bar is fed along the table and is rotated about its axis by means of conical discs 18 which contact with the bottom of the bar. These conical discs are spaced along the length of the table and are driven through a drive shaft 19 as illustrated in detail in Figure 7. The drive shaft (Figure 3) is driven by a motor 20 through a chain 21 and sprocket wheel 22. The drive shaft 19 has a bevel pinion 23 secured thereto by a set screw 24. The pinion 23 drives a pinion 25 secured to an outer spindle 26. The outer spindle carries an inner spindle 27 therein, the outer and inner spindles being connected by a key 28. The inner spindle may be moved upwardly and downwardly to adjust it for different sized bars, by means hereinafter described. The head 29 of the inner spindle has a screw threaded opening for the reception of a screw threaded shank 30 of the conical disc 18. The provision of a screw threaded shank on the conical disc enables the discs to be changed without changing the inner spindle 27.

As shown in Figure 8 the arrangement of the disc 18 and the bar A is such that the center line 32 of the disc does not coincide with the center line 33 of the bar. By this arrangement, when the conical discs 18 are rotated they not only cause the bar A to rotate about its axis, but also impart longitudinal movement to the bar, causing it to be fed toward the grinding apparatus.

70 The adjusting mechanism for operating upon different sized bars is shown in detail in Figures 4, 6, 7, and 8. The bar is guided along the table 2 by guides 35 which are threaded into cross slides 36. The cross slides 75 are guided in ways 37 provided in the guide heads 38. The guide heads 38 are secured to pipes 39 carried by the table. A screw 41 having oppositely threaded ends is threaded into each cross slide 36. Each screw 41 has a 80 bevel pinion 42 secured thereto by a set screw 43. The pinion 42 is rotated by a pinion 44. Pinions 44 are spaced along the shaft 45 which extends the length of the table. The shaft 45 is rotated by a hand wheel 46. Upon 85 rotation of the hand wheel, each screw 41 is rotated. As the ends of the screws are oppositely threaded, the cross slides 36 and the guides 35 are caused to move toward or away from each other. Adjustment of the guides 90 35 relative to the cross slides 36 is accomplished by screwing the guides 35 into the cross slides. This is conveniently accomplished by inserting a spanner into the openings 47 and rotating the guides.

95 When the guides 35 are moved toward each other in order to operate upon bars of smaller size, the conical discs 18 are simultaneously moved upwardly an equal distance in order to maintain the center of the smaller bar in 100 the same plane that the axis of the larger bar occupied. This is necessary in order to maintain correct relationship between the bar and the grinding apparatus. This upward movement of the conical discs 18 when the guides 105 35 are moved toward each other is accomplished by the following mechanism. A pin 48 (Figure 4) is screwed into one of the cross slides 36. The opposite end of the pin 48 is connected to one end of a connecting rod 49. 110 The opposite end of the rod 49 is formed in a yoke 50, which is pivotally connected by a pin 51 to a lug 52 on a cam 53 rotatable about the pipe 39. When the guides 35 are moved toward each other the connecting rod 49 rotates 115 the cam 53 about the pipe 39. The inner end of the cam 53 carries an arm 55. As the arm 55 moves upwardly (Figure 7) it raises an arm 56 carried by a sleeve 57 surrounding the outer spindle 26. The sleeve 57 is slidable 120 upwardly and downwardly in the casing 58. Upward movement of the arm 56 raises the sleeve 57. As the sleeve is raised it raises the inner spindle 27 in the outer spindle 26. No matter what the position of the inner and outer spindles may be the inner spindle is caused to rotate with the outer spindle because of the key 28. By this arrangement, movement of the guides 35 inwardly in order to operate upon smaller size bars automatically 125 130

5 cally raises the conical discs 18, thereby maintaining the axis of the different sized bars in the correct relationship with the grinding apparatus.

10 The ratio of rotation of the bars about their axes to the movement of the bars longitudinally may be changed by varying the distance at which the bars are set off the center line of the conical discs 18. This change in the ratio of rotation to advancement of the bars is accomplished by screwing the guides 35 in the cross slides 36. Movement of the cross slides toward or away from each other is for the purpose of operating upon different sized bars. Movement of the cross slides 36 does not change the relationship of the center line of the bar to the center line of the conical discs 18. This relationship, and therefore the ratio of rotation to advancement of the work is accomplished as above stated by screwing the guides 35 in the cross slides 36.

15 I have illustrated and described the present preferred embodiment of my invention. It is to be understood however that the invention may be otherwise embodied within the scope of the following claims.

20 I claim:

1. Apparatus for feeding bars to a grinding machine, comprising a table, means for feeding a bar along the table, supports for the table, and racks mounted on the supports and extending transversely of the direction of feed, said table having pinions cooperating with said racks.

25 2. Apparatus for feeding bars to a grinding machine, comprising a table, means for feeding a bar along the table, supports for the table, racks mounted on the supports and extending transversely of the direction of feed, guide rails mounted on the supports, guide wheels supported by the guide rails, the guide wheels carrying the table, and pinions carried by the table and adapted to cooperate with said racks.

30 3. A feed table for bars, comprising a conical disc arranged to rotate and cause longitudinal movement of a bar, by contact of the bar at the conical surface of the disc, the disc having a disc spindle, an outer driving spindle in which the disc spindle is axially slideable, a key connecting the disc spindle and the outer driving spindle, and means for rotating said last named spindle.

35 4. A feed table for bars, comprising a conical disc arranged to rotate and cause longitudinal movement of a bar, the disc having a spindle, an outer driving spindle, a key connecting the disc spindle and the outer driving spindle, means for rotating said last named spindle and means for adjusting the disc longitudinally of its axis.

40 5. A table for feeding bars, comprising side guides movable toward and away from each other, a support for a bar, and means connecting the side guides and support for

raising the support as the side guides are moved toward each other.

6. A table for feeding bars, comprising side guides movable toward and away from each other, a support for a bar, a cam operable to raise the support, and means connecting one of the guides and the cam for raising the support as the side guides are moved toward each other. 70

7. A feed table comprising side guides movable toward and away from each other, a rotatable disc adapted to support and rotate and feed a bar along the table, the disc having a spindle, a driving spindle operatively connected to the disc spindle, the disc spindle and driving spindle being relatively movable, means for rotating the driving spindle, and means operable upon movement of the side guides toward each other for raising the disc. 75

8. A feed table comprising side guides movable toward and away from each other, a rotatable disc adapted to support and rotate and feed a bar along the table, the disc having a spindle, a driving spindle operatively connected to the disc spindle, the disc spindle and driving spindle being relatively movable, a sleeve surrounding the driving spindle and supporting the disc, means operable upon movement of the side guides toward each other for raising the sleeve, and means for rotating the driving spindle. 80

9. A table for feeding bars, comprising side guides supported by cross slides, an oppositely threaded screw threaded in the cross slides, means for rotating the screw to move the slides toward and away from each other, a conical rotatable disc supporting a bar and rotating it and feeding it along the table, means connecting one of the slides and the disc and operable on movement of the slides toward each other for raising the disc, and means for rotating the disc. 85

10. A table for feeding bars, comprising side guides supported by cross slides, an oppositely threaded screw threaded in the slides, means for rotating the screw to move the slides toward and away from each other, a conical rotatable disc supporting a bar and rotating it and feeding it along the table, a cam operable to raise the disc, a rod connecting the cam and one of the slides, and means for rotating the disc. 90

11. A table for feeding bars, comprising side guides supported by cross slides, a rotatable disc adapted to support a bar and rotate it and feed it along the table, the center line of the disc and the center line of the bar being offset, means for rotating the disc, and means operable on movement of the slides toward each other for raising the disc, whereby the axes of bars of different sizes are maintained in the same position, said guides being adjustable in their slides in order to vary the 100

distance the bar is set off the center line of the disc.

12. A table for feeding bars, comprising a plurality of rotatable discs for rotating and feeding a bar along the table, a plurality of side guides spaced along each side of the table, means for adjusting the side guides in unison toward the guides on the opposite side of the table, and means operable on movement of the guides toward each other for raising the discs.

13. Apparatus of the character described, comprising a grinding machine, a table for feeding bars thereto, and a table for receiving bars from the grinding machine, said tables having rotatable conical discs arranged to support and rotate and feed a bar along the table, said discs being connected to a common drive shaft whereby the bar is automatically fed through the grinding machine.

In testimony whereof I have hereunto set my hand.

HENRY L. KEHL.
